GOLF CLUB GUIDE

John L. Santoro, Willowick, Ohio

Application October 25, 1957, Serial No. 692,464

6 Claims. (Cl. 273—192)

This invention relates to a device for controlling the head of a golf club during an operating stroke so as to constrain the head to swing in a path parallel to a vertical plane, and to constrain the club face to remain in planes at right angles to said vertical plane at all times during the stroke.

The principal object of the invention is to provide a device which may be detachably connected to a golf club head and which, when so connected, so limits the movement of the golf club head by the shaft that the head can be made to travel only in such a path; which can be positioned so that the path extends in the proper direction for the stroke; and which maintains the head at right angles across the path while at the same time permitting free tilting of the head about both an axis extending along the path of swing so as to permit changing the angle of the shaft relative to the ground and an axis extending transversely of the path of swing so as to change the pitch of the face of the club.

A more specific object is to provide a device which permits the club head to be swung in arcuate paths or to be moved in horizontal or sloping lineal paths, all parallel to a vertical plane, and thus provides for substantial universal movement of the head parallel to said plane while constraining the face of the head to right angles to said plane.

Another specific object is to provide a device of this character and which is practically frictionless so that the stroke made by the player is substantially normal insofar as any resistance thereto is concerned other than the resistance which is deliberately provided for assuring the proper movement of the club head.

Other objects and advantages will become apparent from the following description wherein reference is made to the drawings illustrating a preferred embodiment of my invention and in which:

Fig. 1 is a front elevation of the device with a golf club installed, part of the device being shown in section for clearness in illustration;

Fig. 2 is a right side elevation of the device illustrated in Fig. 1;

Fig. 3 is a sectional view taken on the line 3—3 in Fig. 2;

Fig. 4 is a diagrammatic illustration showing different operating positions of the club and device; and

Fig. 5 is a fragmentary sectional view showing a modification of the device.

Referring to the drawings, the device comprises generally a base or supporting body 1 on which is fixedly mounted a rigid support 2, the base being adapted to rest upon the surface of the ground and being sufficiently heavy to maintain the support in generally upright position.

Mounted on the upper end of the support is a laterally extending portion in the form of an arm 3 to the outer end of which is detachably connected a dependent yoke 4. The yoke 4 is detachably connected to the arm by

2

suitable bolts and nuts 5, for purposes later to be described, and a reinforcing bracket 6 is provided for assuring proper rigidity of the arm and accurate position of the yoke.

5 A pendulum arm 7 is pivotally connected at its upper end to the yoke 4 and is suspended therefrom so as to swing in a vertical plane extending forwardly and rearwardly of the support.

For the purpose of providing an essentially frictionless 10 upper pivotal connection, the pendulum arm 7 is provided at its upper end with a transverse bearing member in the form of a cylindrical rod 8, which is provided at its ends with small dimples or depressions 9. The yoke 4 has depending arms 10 in which are mounted pivot screws 11 which may be locked in adjusted position by means of nuts 12.

As heretofore mentioned, it is desirable that the upper 15 pivotal connection between the pendulum arm 7 and the yoke be substantially frictionless and for this purpose the inner ends of the screws 11 are tapered to a point, as indicated at 13. The inner ends of the screws enter into the depressions or dimples in the end of the rod 8, and the contour of the dimples or depressions is such, relative to the ends of the pins, that substantially only 20 a very small area, approaching closely a point contact, is provided between the pins and the ends of the rod 8. Thus the friction is substantially eliminated, or at least is so reduced that it does not interfere noticeably with the free swinging of the club when the device is 25 in use.

The axis of the upper pivotal connection between the 30 arm 7 and the yoke 4 extends horizontally and transversely of the support so as to be at right angles to a vertical plane parallel to which the arm 7 is to swing. The rod 8 extends laterally of the arm 7 a considerable 35 distance so as to space the pivot points well apart so that they can readily withstand turning moments about axes normal to their axis.

Pivotedly connected to the lower end of the arm 7 is a 35 link arm 15. The arm 15 is connected to the lower end of the arm 7 so as to swing in a vertical plane only about an axis parallel to the axis of the upper pivotal connection of the arm 7. For this purpose, the arm 7 is provided at its lower end with a yoke 16 having arms 40 17 between which one end of the arm 15 is disposed. The arm 15 is provided with a transverse bearing member in the form of a rod 18 corresponding to the rod 8 heretofore described and which is connected to the yoke 16 by means of pointed pivot screws 19.

The connections between the screws 19 and the rod 45 18 are identical in all respects to those heretofore described for the upper pivotal connection of the arm 7 so as to provide a substantially frictionless pivotal connection between the arm 7 and the arm 15.

50 Mounted on the forward end of the arm 15 is a head connecting device, indicated generally at 20. This device comprises a yoke 21 having yoke arms 22 in which are mounted coaxial pointed pivots 23 and 24, respectively, of which the axis is parallel to the axes of the upper and lower pivotal connections provided by the screws 11 and 19, heretofore described.

The pivot 23 is a pointed screw which is adjustable endwise as illustrated. The pivot 24 is in the form of a pin which is slidable axially in one of the arms 22 and is urged axially toward the pin 23 by a suitable spring 25.

55 Thus the pin 24 can be slid endwise away from the pin 23 to permit the insertion of a club head between the inner ends of the pins 23 and 24. The spring 25 supplies only sufficient pressure to seat the pins properly with respect to the head of the club, as is described hereinafter, while permitting the club head to displace the

pin 24 outwardly and thus become free of the device in event of a sudden jerk which would otherwise damage the entire device.

As illustrated in Fig. 1, the device is shown connected to a putter P which has a shaft S, head H, and a putting face F. For the purpose of connecting the head H to the pivots 23 and 24, small dimples, such as indicated at D, are formed at the ends of the head, these dimples being adapted to receive the inner pointed ends of the pivots 23 and 24 and thus provide a substantially free, point contact, pivotal connection between the head H and the yoke 21. Thus the head can be rocked about the common axis of the pins 23 and 24 to change the pitch of its face F.

However, the angle at which the shaft is held by different players varies, and consequently, means must be provided for permitting the rocking of the head H to accommodate the shaft to the angle desired by the particular player. For this purpose, the yoke is connected to the arm 15 for rocking about an axis parallel to the longitudinal axis of the arm 15 which arm is, at all times, constrained to move parallel to the vertical plane parallel to which the head moves when it is moving forwardly and rearwardly.

For this purpose, the yoke 21 is connected on an intermediate arm 26 which, as best illustrated in Fig. 3, is connected to the arm 15 for relative rotation with respect thereto about a common axis of the arms. To provide this connection, the arm 15, which is tubular, is provided with an internal collar 27 in which a pin 28 is secured in coaxial relation with the arm by a cross pin 29. The intermediate arm 26 is provided with a bushing 30 which is secured in fixed position by a crosspin 31 and which rotatably accommodates the pin 28. The pin 28 is provided with a head 32 which bears against the end of the bushing 30 and prevents axial separation of the arm 15 and intermediate arm 26. Thus the arm 26 can rotate about the common axis of itself and the arm 15.

In event the arm 26 should have its axis offset from the arm 15, then it would be arranged so that it could rotate about an axis parallel to that of the arm 15. The bearing connection between the arms 15 and 26 is substantially frictionless insofar as interference with the swinging of the club is concerned.

Thus it will be seen that, due to the pivotal axis at the upper end of the arm 7 being horizontal and extending transversely of a vertical plane parallel to which the club is to swing, the arm 7 can be swung only in a path parallel to a vertical plane extending forwardly and rearwardly of the support.

The arm 15, being connected to the lower end of the arm 7 for swinging about a pivotal axis parallel to the axis of the upper pivotal connection 9, likewise must move parallel to the vertical plane described while being free to swing about its pivotal connection formed by screws 19 relative to the arm 7. The intermediate arm 6, being rotatable about an axis parallel to said vertical plane and to the axis of the arm 15 in all positions of the arm 15, permits the tilting of the club head transversely of the vertical plane about an axis extending forwardly and rearwardly of the path of swing so as to change the angle of the shaft relative to the ground to accommodate the particular player. It does not, however, permit tilting of the head about any axis which is both parallel to said vertical plane and to the face F. Consequently, the face of the head cannot be positioned other than at right angles to said vertical plane. The pivots connecting the head to the yoke 21 are such that the head cannot be shifted out of planes at right angles to the vertical plane.

Thus the club can be manipulated so that the head can be moved to any vertical or horizontal position, parallel to said vertical plane, either forwardly or rearwardly of the support, and high from the ground or on the ground. It can thus be moved in arcuate paths, horizontal paths,

or sloping linear paths, which extend forwardly and rearwardly in a direct line of approach to the ball. The face can be tilted forwardly and rearwardly of the vertical plane to change the pitch of the face, but it cannot be tilted about an upright axis parallel to said vertical plane so as to position the face in a position which would cause the ball to be deflected out of the course intended along the ground.

As illustrated in Fig. 4, this movement permitted is such that the head H can be moved along the ground while the face F is maintained in the proper right angular relation to the proposed path of the ball during travel of the head from a position rearwardly of the support to a position forwardly of the support.

Accordingly, therefore, the device is operable to assure that the stroke made by the operator is properly made.

If desired, a suitable rest or finger 34 is provided on the arm 3 in a position to be engaged by the club shaft S when the club is not being used. Thus, the club head can be tilted to dispose the shaft behind the finger and supported in upright position without detaching the head H from the yoke 21.

Furthermore, on the arm 7 is a snap fastening device or clamp 35 into which the arm 15 or 26 can be snap fastened when swung up into substantial parallelism to the arm 7, for holding the connecting device 20 off the ground and preventing damage thereto when it is not in use.

It is desirable that the device be useful for left and right-hand players. For this purpose, the yoke 4 is made reversible, end for end, by removal of the bolts 5 and rotation of the yoke 180 degrees about a vertical axis, and reattachment in the rotated position by the bolts 5.

However, if desired, instead of the yoke 16, a modified connection may be made between the pendulum arm and the link arm. As illustrated in Fig. 5, there is shown a pendulum arm 37 which is the same in all respects as the arm 7 except that, connected thereto is a yoke 38 which is so connected that the arms thereof extend downwardly, instead of forwardly as in Fig. 2. The link arm 39, corresponding to the arm 15, is pivotally connected to the yoke by a pivot means having a horizontal axis extending transversely of the path of swing. In this arrangement, the arm 39 can be swung to the forward position indicated by dot and dash line 39a in Fig. 5, for use by a right-hand player, but if it is desired, it can be swung to a position at the opposite side of the arm 7, as indicated by the dotted line 39b in Fig. 5, and the device then turned about the upright axis of the support.

It will be apparent from the foregoing description that, by utilizing the device while practicing putting, for example, a true and correct operation of the putter is assured. It has been found that, after a short while of practicing with the movement of the putter constrained to the proper positions by the device, the putting ability of the player is very greatly increased and the poor putting due to misalignment of the face of the club in a direction transversely of the vertical plane parallel to which the club head is swung, and due to bodily movement of the club head back and forth across the normal path, parallel to a vertical plane, in which it should be swung, are eliminated.

Alignment of the device for a particular line of travel of the ball is effected by shifting the base 1 and rotation of the base 1 about a vertical axis.

Thus it is seen that only true forward and rearward swinging motion of the club head parallel to a preselected vertical plane is permitted by the pivots 11; independent components of movement are permitted by the pivots 19; the rocking of the front face of the club about a horizontal axis extending transversely of the path of swing is permitted by the pivots 23 and 24, and the rocking of the club head about an axis extending forwardly and rearwardly of the path of swing is permitted by the pivot pin 28.

Thus the swing of the club is unrestrained except that the plane of the putting face, indicated at F, cannot be rocked about an axis which is both parallel to said vertical plane and parallel to the face F, and thus disposed at an angle transversely of the line of swing.

Having thus described my invention, I claim:

1. A device for the purposes described and comprising a base, a support mounted thereon and having a laterally offset portion spaced above the ground level, a pendulum arm, a link arm, upper transverse horizontal pivotal means pivotally connecting the pendulum arm to said portion and constraining said pendulum arm to swing in a vertical plane extending forwardly and rearwardly of the support, a lower horizontal pivot means pivotally connecting the link arm to the lower end of the pendulum arm at a location spaced below the upper pivotal means and constraining the link arm to move parallel to said plane with the link arm and relative to the link arm, concurrently, a yoke arm, longitudinal pivotal means connecting the yoke arm to the link arm for rocking of the yoke arm about a rocking axis parallel to said plane and to said link arm, said yoke arm having at its forward end a pair of arms between which a golf club head can be accommodated with its opposite ends adjacent the opposite arms, respectively, detachable pivotal means carried by the yoke arms and having an axis disposed in a plane normal to said rocking axis and engageable with opposite ends of the club head and positioned for connecting the club head and yoke for relative rocking movement of the head and yoke arm about the axis of the detachable pivotal means.

2. A device according to claim 1 characterized in that the complementary pivoting parts of each of said pivot means engage each other with substantially point contact.

3. A structure according to claim 1 characterized in that the complementary pivoting parts of said pivot means engage each other substantially frictionlessly.

4. A device according to claim 1 characterized in that part of the pivot means of the yoke arm which engages one end of the club head is spring seated under light pressure and is operative to snap out of engagement with the head when the head is jerked forwardly or rearwardly relative to the yoke arms at speeds substantially greater than those of normal manipulation of the club on a stroke.

5. A device according to claim 1 characterized in that the upper pivotal means is detachably connected to said portion of the support and is adapted to be connected thereto in a position in which the pivotal axis is horizontal and extends transversely of the support with the link arm extending forwardly, and to be reversed and connected in a position in which the upper pivotal means is reversed end for end so that the link arm extends rearwardly, whereby the device can be used by a left-hand golfer as well as a right-hand golfer.

6. A training device for controlling the swing and alignment of a golf club and comprising a base adapted to rest upon the ground in stationary condition, a generally upright support extending upwardly from the base and having a portion projecting laterally from the support, a pendulum arm, upper pivot means pivotally connecting the pendulum arm to said portion for swinging of the pendulum arm about a horizontal axis extending laterally of the support, said pendulum arm normally depending from said pivot means and being freely swingable thereabout from a position rearwardly of a vertical plane through the axis of the upper pivot means to a position forwardly of said plane, a yoke device, pivotal means on the forward end of the yoke device for detachably pivotally engaging opposite ends of the golf club head so as to detachably connect the head to the yoke device for relative rocking movement of the head and yoke device about the axis of the detachable pivotal means, a link arm, lower pivot means connecting one end of the link arm to the lower end of the pendulum arm for swinging of the link arm relative to the pendulum arm about a lower horizontal axis parallel to the axis of said upper pivotal connection, and means connecting the other end of the link arm to the yoke device for relative rocking movement of the yoke device and the link arm about an axis parallel to the vertical plane which extends at right angles to the axes of the upper and lower pivotal means.
